Primary Examiner — Karen S Acker

Assistant Examiner — Andrea Marie McKay

(57) **CLAIM**

The ornamental design for an icicle light assemblage, as shown and described.

DESCRIPTION

FIG. 1 is a front and top perspective view of an icicle light assemblage, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of the selected portion 9 in FIG. 1;

FIG. 10 is an enlarged detail view of the selected portion 10 in FIG. 1;

FIG. 11 is an enlarged detail view of the selected portion 11 in FIG. 2; and,

FIG. 12 is an enlarged detail view of the selected portion 12 in FIG. 2.

The evenly spaced dashed broken lines in the drawings depict portions of the icicle light assemblage that form no part of the claim. The long dash-short dash-long dash broken lines shown in FIGS. 1-2 and 9-12 indicate cutoff boundaries for the enlarged detailed portion views and form no part of the claim.

1 Claim, 12 Drawing Sheets
